UNITED STATES PATENT OFFICE.

JOHN H. STONEMETZ, OF GRAND HAVEN, MICHIGAN, ASSIGNOR TO THE CHALLENGE MACHINERY COMPANY, OF GRAND HAVEN, MICHIGAN; A CORPORATION OF ILLINOIS.

PAPER-CUTTING MACHINE.

1,143,237.

Specification of Letters Patent. Patented June 15, 1915.

Application filed March 19, 1910. Serial No. 550,344.

To all whom it may concern:

Be it known that I, JOHN H. STONEMETZ, a citizen of the United States, and a resident of Grand Haven, in the county of Ottawa and State of Michigan, have invented 5 certain new and useful Improvements in Paper-Cutting Machines, of which the following is a full, clear, and exact specification.

10 This invention relates to paper cutting machines in which a number of layers of paper or card board laid upon a bed plate are simultaneously severed to size, or trimmed as may be, by a reciprocating knife 15 blade, actuated by means of power or hand operative mechanism.

The prime object of this invention is a paper cutting machine of the character above referred to, in which the number and 20 simplicity of parts are reduced to a minimum, and access thereto for adjustment, repairs and the substitution for injured parts substantially promoted and made convenient.

25 Another object of this invention is to have a paper cutting machine so constructed that it may be quickly converted to a hand or power operating machine and vice versa by any ordinary mechanic in the entire absence of cutting, drilling, fitting or machine shop work other than assembling parts previously finished, and thereby reducing the expense of such conversion to a minimum both in cost and time for making the same.

30 A further object is to have the knife blade so constructed as to provide easy access thereto for its removal for substitution for sharpening and other purposes.

35 A still further object is to have the counterbalance so arranged and connected therewith that the machine may be shifted from a hand to a power mechanism and vice versa and the knife blade be removed and reinserted in the absence of the liability of any 40 movement on the part of the knife blade to the injury of the operator making the change.

45 Another object is to have the tape, indicating the position of the knife gage, automatically operated to take up slack therein, and thereby indicate the relative position of the gage to the knife blade at every point of its adjustment.

50 With these ends in view, my invention finds embodiment in certain features of nov-

elty in the construction, combination and arrangement of parts by which the said objects and certain other objects are herein-after attained, all as fully described with reference to the accompanying drawings, 60 and more particularly pointed out in the claims.

In said drawings: Figure 1 illustrates a front end elevation of a paper cutting machine embodying my invention. Fig. 2 is 65 an end elevation of the left hand end of the machine. Fig. 3 is an end elevation of the right hand end of the machine. Fig. 4 is a vertical section. Fig. 5 is an enlarged detail section of the brake, clutch and pulley 70 mechanism for the power shaft. Fig. 6 is an elevation of the inner side of the clutch and pulley for the power shaft. Fig. 7 is a detail end elevation of the stop collar with a pin passing therethrough into the main 75 frame. Fig. 8 is a detail view, in side elevation, of the brake for the power shaft; and, Fig. 9 is a top plan view.

Similar characters of reference indicate the same parts in the several figures of the 80 drawings.

For convenience and clearness of description, the paper cutting machine, containing my invention, will first be described, as constructed, when operated as a power 85 machine.

The base 9 is provided with slot-like openings 10 and 11 in each end thereof extending from a line just below the bottom of a longitudinal power shaft 12 projecting through said openings and supported by plates 13 and 14 rigidly secured to the base by set bolts 15, 16 respectively supporting the boxes 17 and 18 forming the bearings for the power shaft 12, and the sides of the 95 base are also reamed out at 19, 19 for drive shafts 48 and 58.

Mounted upon this base and secured by suitable bolts 20 is a bed plate 21, forming a support for an arch 22 secured thereto by 100 means of bolts 23, the uprights of the arch being provided with slots 24, 25, respectively, registering with the slots 10 and 11 in the base, said base, arch and bed plate are each cast in one piece and so formed that 105 they may be quickly assembled, bolted together and taken apart for shipment, and are of such form that they are readily and conveniently cast and require but little 110 finishing.

- On the power shaft 12 are respectively fast and loose pulleys 26 and 27, the pulley 27 being provided (see Fig. 5) with a clutch ring 28 expandable to tighten the pulley on the shaft by a cone 29 through its engagement with an expanding device 30, the cone 29 being provided with a circumferential groove 31 engaged by opposing pins 31^a projecting inwardly from the bifurcated end 10 of and actuated by a lever 31^b fast about centrally of its length to a pintle 33, having its bearing in a hub 31^c on an arm 34 projecting from the plate 14, to which pintle is also secured a shifting lever 32 by a pin 15 32^a passing through the hub of the lever and the pintle.
- Sleeved on the power shaft 12 is a hub 34^a of a brake wheel 35 preferably covered with leather and opposed by a brake shoe 20 36 forming a part of a lever 37 pivoted to a lateral extension of the arm 34 of the plate 14.
- The brake lever 37 is provided with an upturned end 39 and is actuated to contact 25 with the brake wheel 35 by a spring 40 bearing against the brake lever and supported in its operative position by a pin 41 passing loosely through a slot 42 in the brake lever, said pin being tapped into the brake hub 34^a 30 and provided, at its upper end, with a washer 43 forming a bearing for the upper end of the spring 40, the tension of which may be increased or diminished by means of nuts 44 on the upper end of the pin 41.
- When these several parts are in the position shown in Fig. 5, the clutch is out of its operative position not tightening the loose pulley upon the shaft 12 and the brake lever is in engagement with the brake wheel 35 40 and held in this position by means of an anti-friction roller 45 on the lever 32.
- When, however, the lower end of the lever 32 is moved outwardly, the anti-friction roller 45, by its engagement with the upturned end 39 of the brake lever, will force the brake away from the brake wheel against the resistance of its spring about the time the loose pulley is tightened on the shaft 12, the operation of the shifting lever 32 being 50 performed by hand, as indicated in Fig. 1.
- On the opposite end of the shaft 12 and inwardly of the base structure, is a worm gear 46 in constant engagement with a worm gear 47 on a short drive shaft 48, and on the outer end of the shaft 12 is a clutch crank 49 for operating the power shaft independently of power mechanism, when, for any purpose this may be necessary as herein-after more specifically referred to.
- On the worm gear wheel 47 is a stud 50, provided with a perforation for a spring key 51 for securing a lever 52 thereon, the upper end of said lever projecting (see Figs. 1 and 9) between the grooved or bifurcated arms 53^a, 53^b, projecting from a cutter blade

head 53, by means of a pivot bolt 54, on the outer projecting end of which is also pivoted a counter-weight lever 55, the lower end of which is connected with a lug 56 by means of a pivot 57 projecting from said lug.

The lug 56 projects from a hub 58, sleeved on a short shaft 58^a, and from which depends an arm 59 suspending a counter-weight 60.

The knife head is suspended by means of (see Fig. 1) links 61 and 62, pivoted to the outer ends thereof, and at their upper ends to the arch, with the result that the cutter blade in operation has a swinging movement 80 producing a shear-like cut through the paper resting upon the bed plate, and, together with its head, is so balanced at every point of its movement that its operating lever and other actuating devices are relieved from all strain due to the very considerable weight of the cutter head and blade.

The cutter head 53 is provided with a recess 63 (see Fig. 4) in which the shank of a cutter blade 64 is seated, the cutter blade being provided at intervals of its length with lugs 65 having elongated slots 66 for the passage of bolts 67 screw-threaded in the head for clamping the cutter blade thereto, the cutter blade 64 being adjusted in its head with reference to the bed plate by means (see Fig. 1) of screw bolts 68 made for the first time accessible from the front of the machine, by means of slots 69, 69 through the cutter head, the heads of such bolts being provided with perforations 70 at intervals whereby the bolts may be conveniently and quickly adjusted by means of a straight pin or even a wire nail, when, as heretofore constructed the bolts were only accessible from the top of the knife head or bar, or by means of a pin wrench from behind, which is not only inconvenient but a waste of time entirely avoided by rendering these adjusting bolts accessible from the front of the machine where the bed plate and the edge of the knife are in view throughout the adjustment desired to be made.

When installing a cutting blade it is first loosely suspended by its lugs 65 from the bolts 67 with the edge resting by the gravity of the blade upon the opposing surface of the bed plate, then the lever screws 68 are 120 turned until their heads are in contact with the back edge of the blade structure, and after this is done the bolts 67 are tightened and the blade thereby clamped to its head in a position of perfect adjustment relative to the bed plate, so that when it descends through the paper it will cut through the bottom sheet as perfectly as it will the sheets above the same.

The bed plate 21, toward its rear edge 130

(see Fig. 4) is provided with a groove 71 for holding the stick 72 with which the cutting blade contacts on passing through the cut paper, and to better sustain the force of the blade the bed plate is thickened at this point as shown in Fig. 4, and supported (see Figs. 1 and 4) at intervals upon screws 72^a, 72^b, adjustable in cross bars 72^b, 72^b, connecting the opposing sides of the base support, whereby the bed plate is adjusted against bending or sagging under the force of the cutter blade.

The bed plate (see Figs. 1 and 9) is cast with a slot 73, and with an end bar 74, upon which is mounted a gage block 76 of the usual sectional construction, secured to a slide block 77, to which the central section of the gage block is secured by a screw bolt 78, said block being provided with internal screw threads 79 engaged by screw threads 80 upon a shaft 81, which shaft, at its rear end, is centered upon an adjustable screw 82, working in a lug 83, depending from the end bar 74, and locked in its adjustment by a nut 75.

The forward end of the shaft 81 projects through the wall of the base, and has its bearing in a bracket 84 depending from the bed plate, which bracket also supports a pivot bolt 85 screwed therein, forming the bearing for a hand operative wheel 86 provided with internal gear teeth 87 meshing with a pinion 88 on the end of the shaft 81.

In locking the hand wheel against accidental movement, (see Fig. 1) a bracket 81^a is secured by screw threaded bolts 81^b, 81^b to the underside of the bed plate 21, and provided with a thumb screw 81^c adapted to be tightened against the periphery of the hand wheel 86.

As heretofore constructed the actuating shaft of the gage block has been operated by a crank arm attached directly to the end of the shaft, with the result that much time and labor have been lost in adjusting the gage, and particularly from one extreme to the other of its adjustment, and while this has long been an objection I am seemingly the first to employ in a paper cutting machine a pinion and gear by which to provide a means for causing the adjusting screw to make a plurality of revolutions for one revolution of a hand wheel, or, as indicated in the drawings, four revolutions to one complete revolution of a hand wheel actuating it.

The gage block 76 (see Figs. 4 and 9) is in three sections, 76^a, 76^b and 76^c, the sections 76^a and 76^b being provided with flanges 89, and longitudinal of the central section 76^c are slots 89^a through which slots pass thumb screws 90 screwing into adjacent side flanges 89 of the sections 76^a and 76^b, thereby providing for so adjusting the gage that the cutter bar may simultaneously trim

two ends and one side of a book or other pile of sheets to rectangular form, as indicated by the adjustment of the gage block in Fig. 9.

As a means for adjusting and securing the gage block in alinement, or, if desired for any purpose out of alinement with the cutter knife, section 76^c of the gage block is provided with parallel lugs 78^a, 78^a, forming bearings for the ends of a threaded shaft 78^b which is loosely confined in the slot of a lug 92 (see Figs. 4 and 9) projecting from the slide block 77 through a slot in the section 76^c.

On the screw threaded bolt 78^b at each side of the lug 92 are nuts 92^a, which, by their adjustment upon the right and left screw threaded bolt 78^b are adapted to swing the section 76^c laterally upon a pivot formed by the bolt 78 until the gage block is in or out of alinement, as may be, with the cutter knife, the gage block being secured in its adjustable position by tightening the nuts 92^a against the lug 92 and the tightening of the bolt 78.

Mounted upon the gage block section 76 (see Fig. 4) is a post 93 rising to about a plane with the underside of the top of the arch 22, which post has secured to its upper end a tape, preferably of steel, adjustable by means of a screw threaded pin 95 secured to the tape and passing through the post 93 to which it is locked by means of opposing nuts 96, 96, the tape passing thence around a drum 97 pivoted to the underside of the arch and having an internal coiled spring (not shown) automatically winding up the tape as the gage block is moved toward the arch.

The gage 94 is preferably provided with gage marks for indicating the proximity of the gage block to the cutting knife, and, to this end, for the convenience of the operator, a finger 98 is secured to the arch just above the drum (see Fig. 1) by means of a screw 99 directly in front of the operator, to point the approaching figures and lines on the tape.

Rising from the flange 91 is an upright 100 supporting a paper clamp comprising a jaw 101, working vertically in the shank 102 of which is a screw 103 secured to a hub 104 of a hand wheel 105, by means of which the clamp may be raised and lowered after the gage block has been adjusted so that the paper may be held firmly upon the bed plate directing the operation of the cutting knife in severing the paper, the front wall of the clamp affording a bearing surface for the knife and the head 53 to which the blade is secured.

In the operation of my paper cutter as a power machine the normal position of the cutting blade is at the limit of its upward stroke and is caused to move from that po-

sition by pushing upon the lever 32 until the clutch on the power shaft 12 expands the clutch ring and tightens the pulley 27 on said shaft which will then revolve as soon as the usual belt (not shown) is shifted from the loose pulley to the clutch pulley by any belt shifter commonly employed for that purpose, but as soon as the cutting blade has returned to the limit of its up stroke the position of the shifting lever 32 is automatically reversed and the clutch thrown out of engagement with the loose pulley by means of a bent lever 106 (see Fig. 1) pivoted to the shifting lever 32, as indicated at 107, above the fulcrum thereof and to a stud 108 on the worm gear 47, with the result that the cutting blade remains in its elevated position until the shifting lever 32 is operated to again move the clutch to its position tightening the pulley 27 on its shaft.

When, for any reason, it is desirable to actuate the cutting blade independently of the power mechanism the clutch crank 49 may be used for that purpose.

Having so far described the embodiment of my invention in a power operating machine, it is important to note, at this point, that the prime object of my invention is to have a paper cutting machine so constructed that they may be operated by hand until a time when it may become necessary to operate it by power, and that when this time arrives it may be quickly converted from a hand to a power operated machine and at a minimum expense.

In other words, when a hand operated machine of my invention is ordered with a view to its possibility of it subsequently being operated by power, as is usually the expectation, all of the necessary machine work upon the base and other parts of the machine for the transformation are completed, and the machine is shipped without being accompanied with the power shaft 12, the pulleys, the worm gear and its shaft, or any of the clutch operating mechanism therefor, but, (see Fig. 3) with a hand operated lever 109 (shown in dotted lines in Fig. 1) secured to the drive shaft 58, upon which is a crank arm 110 (see Figs. 1 and 3) provided with a removable stud 111 upon which the lever 52 is then secured, with the result that the lower end of the lever 52 is oscillated by the hand lever instead of being continuously revolved as it is when driven by power mechanism from the worm gear 47.

Keyed on the drive shaft 48, when the machine is operated by hand, is (see Fig. 7) a collar 112 from which radially projects two studs 113 and 114 operating to limit the movement of the lever 109 in both directions by alternately engaging a semi-boss 115 formed with and projecting from the machine base. In other words, when the lever

is at the limit of its up-stroke, the stud 114 will be in engagement with the boss, as shown in Fig. 7, and, accordingly limit the movement of the hand lever in that direction; the engagement of the stud 113 with the boss, when the lever is swung, will likewise limit its downward movement.

When the hand lever is at the limit of its upstroke the cutting knife is in its highest position and may be locked in this position against accidental falling to the injury of the operator when the machine is not being operated, or when it is desirable to remove the knife for sharpening purposes, and particularly when making the changes necessary to shift the machine from a hand to power operation, in which connection it should be observed that the lever 55, being permanently connected with the crank arm of the counter weight 60, the knife blade is continuously balanced at all times.

The hand lever 109 and the stop collar 112 (see Figs. 1, 2, 7 and 8) are removably secured to the drive shaft 58 by keys 116 and 117 (see Fig. 1), as a means by which the machine may be converted from a hand to a power machine and vice versa.

When it is desirable or necessary to change the machine from hand to power operated, the owner need but so notify the manufacturer in general terms when he will be furnished with the power shaft 12, the several devices mounted and supported thereon, including the bent lever 106, and when received it is only necessary for the installation of these power operating devices to fasten the plates 13 and 14 to their base already tapped to receive the bolts 16 at each end of the machine, insert therein the boxes and the shaft 12 and secure the other devices supported by the shaft in their operating position as shown in Fig. 1, all of which it will be seen may be readily and quickly accomplished in the absence of any shop work other than assembling.

By my invention the cost of construction of a hand operated machine and its subsequent conversion into a power operated machine is reduced to a minimum, for in casting the base there is no additional cost due to casting the base with end slots through which to project the power shaft, nor for the boss 115 for the drive shaft 48, and substantially no cost for tapping the holes therein for the bolts 16 of the end plates 13 and 14, which slots, boss and screw holes will be the only additions to be made in the base by which to adapt it to a power machine, and without adding substantial cost to the production of a hand operated machine, even though never used for power operating purposes, a machine of my invention, by reason of its convertibility, embodies advantages not only in operation but desirable to a substantial advantage both to the manufacturer

and purchaser, and particularly the latter when his business assumes such proportions that a power operated machine is necessary.

- These changes are largely due to the employment of the drive shaft 48, providing, as it does, for the support and actuation of the worm gear wheel and a crank arm from one to the other of which may be shifted a lever directly connected with and actuating the cutting knife at will either by hand or power, which drive shaft further provides for suspending the counter-balance weight entirely within the base out of sight and out of the way of the operator, and a permanent lever connection between the counter-balance weight and the cutting knife, and in such a manner there is such a constant tendency of the weight to sustain the cutting knife at the limit of its upward stroke when removing the knife for sharpening and in changing the machine from hand to power operated or vice versa as may be.

It is proper at this point to suggest that when a cutting knife is to be operated by hand power, a lever, and particularly such as the hand lever 109, is best adapted for the application of power to the knife, especially when cutting through a very considerable thickness of paper, and as distinguished from a power machine hand operated by means of a crank on one end of the power shaft and which is not the purpose of the clutch crank arm 49, its only intended function being that of turning the power shaft to and only to whatever extent may be necessary for shifting the several parts of the machine from one position to the other when making repairs, and, to which end, the crank arm 49 may be thrown out of operation by simply slipping it off the end of the power shaft 12.

Having described my invention, what I claim and desire to secure by Letters Patent is:—

- 45 1. A paper cutting machine comprising in combination a cutting knife, a drive shaft therefor, a worm gear, a crank arm, and a lever pivotally connected with the cutting knife and adapted to be shifted from the 50 crank arm to the gear whereby the cutting knife may be operated by hand or by power as may be, substantially as described.

2. A paper cutting machine comprising in combination a swinging cutting knife, means for suspending said knife in its operative position, a drive shaft therefor, a counterbalance weight on said shaft, a lever pivotally connecting said weight and cutting knife, a crank arm on said shaft, and 60 a lever pivotally connecting said crank arm with and actuating said cutting knife, substantially as described.

3. A paper cutting machine comprising in combination a cutting knife, a drive shaft, a crank arm and gear on said shaft,

a lever pivotally connected at one end to the cutting knife and adapted to be shifted from the crank arm to the gear, and means for actuating the gear when so shifted, substantially as described.

70

4. A paper cutting machine comprising in combination a base, a cutting knife pivotally suspended above said base, a drive shaft, a counterbalance weight suspended from said shaft inside the base, a lever pivotally connecting said weight and cutting knife, a crank arm upon the drive shaft, and a lever pivotally connecting said crank arm and the cutting knife, substantially as described.

75

5. A paper cutting machine comprising in combination a swinging cutting knife, means pivotally suspending said knife, a drive shaft, a counterbalance weight suspended from said shaft, a lever pivotally connecting said weight with the cutting knife, a crank arm upon said shaft, a lever pivotally connecting said crank arm with the cutting knife, and a hand operated lever secured to said shaft, substantially as de- 80

85

90 6. A paper cutting machine comprising in combination a base support, a cutting knife, means suspending said knife in a swinging position, a drive shaft, means connecting said shaft with the cutting knife, a hand operated lever upon said shaft, and stops respectively upon said shaft and the base of the machine limiting the movement of the hand lever, substantially as de- 95

100

105 7. A paper cutting machine comprising in combination an arch, a vibrating cutting knife, means pivotally suspending the knife from said arch, a drive shaft, a lever connection between the drive shaft and said knife, a hand actuating lever secured to said shaft, means limiting the movement of the hand lever, and means for locking said lever at one limit of its stroke and thereby the cutting knife at the limit of its upward movement, substantially as described.

110

115 8. A paper cutting machine comprising in combination a base support, an arch mounted upon said support, a swinging cutting knife, means suspending the cutting knife from said arch, a drive shaft, a crank upon and a counterbalance weight suspended from said shaft, levers respectively pivotally connecting said counterbalance weight 120 and crank arm with the cutting knife, a hand operating lever secured to said shaft, and a pin device adapted to simultaneously lock said lever and the cutting knife at the limit of their upward movement, substantially as described.

125

9. A paper cutting machine comprising in combination a base, an arch, a cutting knife, means suspending said knife in its operative and operating position, a drive shaft, a 130

- crank arm and a hand operating lever upon said shaft, a counterbalance weight secured to and depending from said shaft, levers respectively connecting said crank arm and 5 weight with the cutting knife, a hand operating lever on said shaft adapted to move the cutting knife to the limit of its up stroke, a worm gear upon the drive shaft, a power shaft, a worm thereon adapted to 10 engage said gear, and means for locking the cutting knife at the limit of its upward stroke when assembling the power shaft with the machine, substantially as described.
- 15 10. A paper cutting machine comprising in combination a base, a bed plate, an arch, a cutting knife pivotally suspended from said arch, a drive shaft, a counterbalance weight suspended within the base from said 20 shaft and means connecting said weight with the cutting knife, a worm gear and a crank arm upon said shaft, a lever pivotally connected with and for actuating said cutting knife and adapted to be shifted from 25 the crank arm to the worm gear, a power shaft extending through and removably supported from the base, a worm upon said shaft engaging and actuating said worm gear, a loose pulley upon said power shaft, 30 a clutch for the loose pulley, a hand lever for actuating said clutch to lock the loose pulley upon the power shaft, and means automatically disengaging the clutch therefrom when the cutting knife is at the limit 35 of its upward movement, substantially as described.
11. A paper cutting machine comprising in combination a cutting knife, a power shaft, means connecting said power shaft 40 with and operating said knife, a loose pulley upon said shaft, clutch devices adapted to lock the pulley to the shaft, a hand lever for moving said clutch to engagement with the pulley, a brake wheel on said shaft, a 45 brake automatically actuated to contact therewith, and means connecting said brake with the hand lever whereby the brake is moved to engagement with the brake wheel concurrently with the movement of the hand lever disengaging the clutch from the loose pulley, substantially as described.
12. A paper cutting machine comprising in combination a cutting knife, a drive shaft, means connecting the drive shaft 55 with and actuating the cutting knife, a gear wheel upon said drive shaft, a power shaft, means upon said power shaft for actuating said gear wheel, a loose pulley upon the power shaft, a clutch therefor, a hand lever 60 actuating said clutch to engagement with the loose pulley, and a lever connection between said hand lever and gear wheel whereby the hand lever and the clutch are automatically actuated to disengage the
- clutch and loose pulley when the cutting 65 knife is at the limit of its upward movement, substantially as described.
13. A paper cutting machine comprising in combination a cutting knife, a drive shaft, a gear wheel upon said shaft, means 70 connecting said gear wheel with and actuating said knife, a power shaft, means operatively connecting said power shaft with said gear wheel, a crank arm upon the power 75 shaft for shifting the cutting knife to a position for its removal and insertion independently of power operating mechanism, substantially as described.
14. A paper cutting machine comprising in combination a cutting knife, means for 80 operating said knife, a bed plate, a gage block mounted thereon, a screw threaded shaft for adjusting said block, a pinion upon the forward end of said shaft, a gear wheel meshing with said pinion and a crank 85 handle upon said gear wheel whereby the screw shaft will be revolved a plurality of times through one revolution of the gear wheel and the adjustment of the gage block be quickened and facilitated, substantially 90 as described.
15. A paper cutting machine, comprising in combination a base, a bed plate, an arch, a cutting knife suspended from said arch, means for actuating said knife, a gage block, 95 a screw threaded shaft for actuating said gage block, a pivot support therefor projecting from the bed plate, means supporting the opposite and forward end of said shaft, a pinion on said shaft, and a hand 100 wheel provided with internal teeth meshing with said pinion whereby said gear is isolated from contact with the operator and the movement of the gage block is substantially quickened as herein described. 105
16. A paper cutting machine comprising in combination a gage block, a spring actuated drum pivoted upon a fixed part of said machine, an indicator tape windable upon said drum, and means connecting one end 110 of said tape with the gage blocks whereby in the adjustment of the gage block the slack of the tape is automatically constantly taken up and the relative position of the gage block to the knife is accurately indicated at all times of adjustment of the gage block, substantially as described. 115
17. A paper cutting machine comprising in combination an adjustable gage block, a post supported by said gage block, an arch, 120 a spring actuated drum pivoted to said arch, an indicator tape wound upon said drum and having its outer end secured to said post, substantially as described.
18. A paper cutting machine comprising 125 in combination an adjustable gage block, a post rising above and supported thereon, an arch, a spring actuated drum pivoted upon

the under side of said arch, an indicator tape wound thereon, and an adjustable connection between the outer end of said tape and post, substantially as described.

5 19. A paper cutting machine comprising in combination a base, a single piece bed plate mounted thereon, an arch, a cutting knife, links pivoted to the arch and to the cutting knife and suspending the latter in its opposite position, a gage block adjustable on the bed plate, a post secured to and projecting above said gage block to about the plane of the under side of the arch, a spring actuated drum pivoted to the under side of said arch, an indicator tape wound thereon, and means connecting one end of said tape with the post, substantially as and for the purposes described.

20. A paper cutting machine comprising in combination a reciprocating cutter knife, a bed plate transversely thickened upon its underside, and adjustable means for supporting said bed plate against bending or warping in the line of movement of an opposing cutter knife, substantially as described.

21. A paper cutting machine comprising in combination a reciprocating cutter knife, a bed plate transversely thickened on a line in the path of travel of the cutter knife, and means adjustably supporting said thickened portion at intervals of its length directly be-

neath and opposite the edge of the cutter knife, substantially as described.

22. A paper cutting machine comprising in combination a cutter knife, a bed plate, a sectional gage block, means for adjusting said sections with reference to each other, a screw threaded shaft and hand wheel for adjusting said gage block with reference to the path of travel of the cutting knife, and means directly and positively locking said gage block shaft and hand wheel against accidental movement, substantially as described.

23. A paper cutting machine comprising in combination a gage block composed of a plurality of transverse sections, means for adjusting said sections with reference to each other, means for simultaneously adjusting said gage block in its entirety with reference to the path of travel of the cutter knife, and means for likewise laterally adjusting said sections at an oblique angle to the path of travel of the cutter knife, substantially as described.

In witness whereof, I have hereunto set my hand and affixed my seal, this 27th day of January A. D. 1910.

JOHN H. STONEMETZ. [L. S.]

Witnesses:

HENRIETTA KIEL,
H. Z. NYLAND.
